UNITED STATES PATENT OFFICE.

HERMANN AUGUST LOUIS CARL KAHLE AND FREDERICK WILLIAM KIRCHHOFF, OF NEW ORLEANS, LOUISIANA.

UMBRELLA OR PARASOL.

SPECIFICATION forming part of Letters Patent No. 408,721, dated August 13, 1889.

Application filed May 29, 1888. Serial No. 275,467. (No model.)

To all whom it may concern:

Be it known that we, HERMANN AUGUST LOUIS CARL KAHLE and FREDERICK WILLIAM KIRCHHOFF, citizens of the United States, residing at New Orleans, in the parish of Orleans and State of Louisiana, have invented new and useful Improvements in Umbrellas and Parasols, of which the following is a specification.

This invention relates to umbrellas, parasols, and similar articles, and has for its object to provide novel, simple, and efficient means whereby the cover can be removed and replaced and interchanged or removed without the aid of a skilled workman; and to such ends the invention consists in the features of construction and combination of devices hereinafter described and claimed, reference being made to the accompanying drawings, in which—

Figure 1 is a sectional elevation of part of an umbrella, showing the manner of detachably securing the center of the cover to the rib-holding disk on the umbrella-stick; Fig. 2, a similar view of the same, showing a modification; Fig. 3, a longitudinal and a cross-sectional view of one of the removable tips; Fig. 4, similar views showing a different form of removable tip; Figs. 5, 6, 7, 8, and 9, detail views showing modifications of the tips; Fig. 10, a detail side view showing a clamp for connecting the cover to the ribs along their length; and Fig. 11, a sectional view on the line X X, Fig. 10.

In order to enable those skilled in the art to make and use our invention, we will now describe the same in detail, first referring to Fig. 1, wherein—

The numeral 1 indicates the umbrella-stick; 2, the disk fastened to the stick, and to which the ribs 3 are secured in the usual manner, and 4 the umbrella-cover of suitable fabric. The stick at a point above or outside of the rib-holding disk 2 is provided with a recess 5, in which is secured at its upper end a spring 6, having at its lower end a lateral pin or lug normally projecting out beyond the surface of the stick. A sleeve 7, having a bell-shaped collar or lower portion 8, is adapted to slide on the stick over the spring and its pin until the upper end of the sleeve falls beneath the

pin or lug at the lower free end of the spring, when the latter will spring outward and lock the sleeve in place with the lower edge of its collar binding the cover 4 upon the rib-holding disk 2. The upper end of the sleeve 7 is inclined or cam-shaped, as at 9, to bear against the pin on the spring 6, so that by turning the sleeve in the proper direction its collar 8 will be forced tightly against the disk to firmly bind and hold the cover in proper position.

In the modification shown in Fig. 2 the umbrella-stick 1 is provided at a point above the rib-supporting disk 2 with two opposite springs 20, having laterally-projecting pins 21 at their lower extremities, and the sleeve 7 is supplied with two opposite holes 22, so that when the sleeve is moved down to cause its collar 8 to bind the cover 4 on the disk 2 the lateral pins 21 will spring into engagement with the holes 22, and thereby firmly hold the sleeve in place to bind the cover on the disk.

The removable sleeve, by the spring-pins and clamping-collar 8, so holds the cover that the latter can be removed and replaced or interchanged at will. To permit the removal of the cover entirely from the umbrella and provide for replacing it or another cover without skilled labor, we provide the removable tips, which are sewed to the cover and can be slid upon or off the outer ends of the ribs by bending the latter to shorten the distance between the rib-attaching disk 2 and the outer extremities of the ribs.

In Fig. 3 the tip 24 is tubular and pointed at its outer end, and is provided with an eye 25, by which to connect the tip with the cover by sewing or stitching with cotton or other thread or strands. These tips constitute an attached part of the cover in contradistinction to being fixed parts of the ribs, and they can be quickly slipped upon or off the extremities of the ribs by bending the latter upwardly, and thereby shortening the distance between the rib-carrying disk 2 and the outer extremities of the ribs, while the tips are securely retained in place and prevented from accidental detachment by the tension of the cover when the ribs stand in their normal position. When the umbrella is raised, the cover is placed under increased tension, and conse-

quently the tips are more firmly and securely held in engagement with the ribs.

In Figs. 5, 6, 7, 8, and 9 the umbrella-ribs 3 are shown tubular; but they may be solid.

5 In Fig. 3 the tubular tip is provided at its inner end with an inwardly-projecting lip 27, to enter the groove in the rib, and with a perforated teat 26, by which to connect it at a point remote from the eye 25 with the inner side of the umbrella-cover.

The tip Fig. 3 is circular in cross-section to fit a correspondingly-shaped rib, while in Fig. 4 the tip 24 is formed to fit a U-shaped rib, and the lip 27 is omitted; but it is provided with the eye 25 to stitch it to the cover.

15 In Fig. 5 the tip 24 is provided with the eye 25 and a reduced tenon 28 to slip into the outer end of the tubular rib 3.

In Fig. 6 the tip 24 is tubular and fitted 20 over the umbrella-rib 3, having a tip of the usual construction.

25 In Fig. 7 the tip 24 has the eye 25 and teat 26, and is provided at its inner end with a slot or socket 29 to slip upon or off a tenon on the outer end of the rib 3.

30 In Figs. 8 and 9, the tip having the eye 25, is tubular and longitudinally slotted, as at 31, and is slipped over the end of the grooved rib 3, and the edges of the slot 31 of the tip are 35 bent inward to underlie the edges of the grooved rib. As all the tips are secured to the cover and are detachable from the ribs, and as the cover is detachably held at the center on the rib-holding disk by the spring-pins, it will be obvious that any person can quickly 40 remove and replace the cover or interchange covers. For the purpose of detachably connecting the cover to the ribs at different points along their length, we may provide the spring-clamps 32, Figs. 10 and 11, each formed of a

piece of spring-metal to form two spring-jaws 33, to slip over and engage the rib and provided with an eye 34 (one or more) to stitch or sew the inside of the cover to the clamp; but as such clamps are known they are not 45 herein claimed.

Having thus described our invention, what we claim is—

1. The combination, with the stick having a rib-carrying disk and a vertically-sliding 50 sleeve for binding the cover in place, of a laterally-projecting spring-pin connected with the stick and springing into engagement with the sleeve when the latter is moved down upon the cover, substantially as described. 55

2. An umbrella or parasol consisting of a stick having a stationary rib-carrying disk, a vertically-sliding sleeve mounted on the stick above said disk to clamp the cover thereupon, tips stitched to the cover and detachably engaging the ribs, and a spring secured to the stick and provided with a laterally-projecting pin which springs into engagement with the sleeve when the latter is moved down upon the cover, substantially as described. 60

3. An umbrella or parasol consisting of a stick having a rib-carrying disk and provided with a spring having a lateral pin, a rotating and vertically-sliding sleeve having an inclined upper end and a collar at its lower end, 70 the cover and tips stitched to the cover and detachably engaging the ribs, substantially as described.

In testimony whereof we affix our signatures in presence of two witnesses.

HERMANN AUGUST LOUIS CARL KAILE.
FREDERICK WILLIAM KIRCHHOFF.
